UNITED STATES PATENT OFFICE.

CARL SEGNA, OF NEW YORK, N. Y.

DESIGN FOR A SPEED-WAGON AXLE.

SPECIFICATION forming part of Design No. 34,003, dated January 29, 1901.

Application filed December 29, 1900. Serial No. 41,538. Term of patent 8½ years.

To all whom it may concern:

Be it known that I, CARL SEGNA, a citizen of the United States, residing in New York, (Brooklyn,) Kings county, State of New York, 5 have invented and produced a new and original Design for Speed-Wagon Axles, of which the following is a specification.

The accompanying drawing, forming a part hereof, is a longitudinal elevation of a speed-wagon axle, showing my design.

In the structure, 1 is the main member of the axle, having curved portions 2 and right-angled extensions 3. 4 represents the wheel-spindles, provided with inwardly-projecting 15 portions 5. The spindles 4 are united at 6 to the extremities of the extensions 3 and at

their inner ends to braces 7 and 8, which pass therefrom to the extensions 3 and the main member 1 of the axle, respectively.

Having described my invention, what I 20 claim, and desire to secure by Letters Patent, is—

The design for a speed-wagon axle, as herein shown and described.

Signed by me in the borough of Brooklyn, 25 county of Kings, State of New York, this 17th day of December, 1900.

CARL SEGNA.
